HOLDER FOR NOTE PAPER

Stanley R. Curtis, Toledo, Ohio

Application February 24, 1947, Serial No. 730,219

4 Claims. (Cl. 281—44)

1

This invention relates to holders for note paper and, more particularly, to a device for holding a plurality of loose note or memo sheets which are in position so that the top sheet of the several sheets is exposed for use and so that after notes are made on the top sheet it can be quickly and easily removed from the holder without removing or loosening the remaining sheets in the holder.

Various devices have been developed for holding small note or memo pads or sheets of paper. Usually these devices consist of holders for padded sheets of paper so that each sheet as used must be torn from the pad. While this accomplishes one purpose of such a device, namely, the holding of a sheet of paper so that a person writing notes can write freely without having to hold the paper in place, it is less than desirable because each sheet of paper must be separately torn loose from the pad.

Other devices have been developed which merely hold loose sheets of paper and thus each sheet need not be separately torn from a pad but in most instances these devices hold all the sheets on edge in small vertical compartments or hold them horizontally in box-like receptacles. In either case a sheet cannot be used for making notes unless first individually removed and placed on a writing surface, where it must be held with one hand while writing with the other.

It is the principal object of the present invention to provide a small neat device which will hold a considerable quantity of loose cards or sheets of memo or note paper in position so that the top card or sheet can be written upon without interference and so that it will remain in place while being written upon and need not be held by a writer's free hand. This is particularly advantageous when notes are being taken of telephone communications.

It is a further object of this invention to provide such a loose memo sheet holder in which the uppermost sheet after having been used can be quickly whisked from the holder without having to be torn loose.

It is a further object of this invention to provide a memo sheet holder which automatically accommodates itself to the depletion of a stack of memo sheets being held in the holder and grasps a

single sheet as tightly as a group of sheets or vice versa.

It is yet another object of this invention to provide a memo sheet holder which has but two parts, each simple and inexpensive to construct.

And still another object is to provide a desk accessory capable of clever attention attracting manipulation which therefore is adapted for exploitation as an advertising device.

10 More important objects and advantages are apparent from the drawings, in which:

Figure I is a perspective view of a note paper holder embodying the invention being shown with a pad of note or memo papers inserted 15 therein, the paper being broken away to show certain details of construction of the device.

Figure II is a vertical sectional view taken substantially from the position indicated by the line II—II of Figure I.

20 Figure III is a vertical sectional view taken substantially from the position indicated by the line III—III of Figure I.

A memo pad holder embodying the invention consists of two main parts, a base 1 and a paper 25 retainer 2. The base 1 may be molded as a single piece from a plastic or a synthetic resin as, for example, from phenol-formaldehyde, in finishes approximating in appearance various woods such as walnut and mahogany, or it may be molded from melamine-formaldehyde or urea-formaldehyde in materials having desired color or combination of colors. The base 1 also may be stamped of sheet steel or aluminum alloy, die 30 cast of suitable metal, or be molded of glass, ceramics or papier-mâché or it may be constructed of wood.

The general shape of the base 1 is that of an inverted tray and it should be of approximately one-half inch deep in order to provide clearance 40 for the automatic retainer 2. In order that it may be most comfortable for the jotting of notes on sheets held in place on the base 1, the base should not be greatly thicker than one-half inch.

The base 1 is provided with a flat top and four 45 preferably slanting or styled skirts 3 on which small advertising plaques, labels or decalcomanias can be mounted to carry advertising messages or to merely give the name or other data concerning the person or firm furnishing the device. If the 50 device is not used for advertising purposes the

outermost surfaces of the skirts 3 can be finished in any desired manner depending upon the material from which the base 1 is made.

One of the functions of the retainer 2 is that of a paperweight. Hence, it preferably should be formed from a relatively heavy metal as, for example, say, about 20 gauge steel. The paper retainer 2 has a main body 4 which is suspended within the base 1 beneath the flat upper surface of the base 1. At the ends of the body portion 4 of the retainer 2 are end pieces 5 which extend upwardly through a pair of transverse slots 6 molded or otherwise cut or formed near the front and rear ends of the flat top of the base 1. Each of the end pieces 5 is turned over horizontally toward the center of the device to form a retaining lip 7 which rests on the upper surface of the uppermost sheet of paper retained in the device.

At one side of each end piece 5 (in the drawings, the left side in Figure 1) there is a stop 8 which extends across from the edge of the body portion 4 along the end piece 5 to the lip 7. Each of the stops 8 extends through a short longitudinally extending slot 9 also molded or cut in the flat top of the base 1 and joining the slot 6 to which it is adjacent.

The end pieces 5 constitute hangers to support the main body 4 of the retainer and also operate as guides to direct its movement up and down. They also form end walls of a receptacle for the stack of cards or sheets of paper to be held and act as guides along which the stack may be inserted and along which the discrete cards or sheets successively may be withdrawn.

The lips 7 constitute hooks at the tops of the end pieces which prevent the retainer from dropping out of position and also operate as lightly applied clamps to prevent accidental displacement of the cards or sheets of paper.

The entire paper retainer (comprising its main body 2, its ends 5, lips 7 and stops 8) moves up and down in the slots 6. When the supply of cards or sheets is to be replenished the user simply picks up the base with one hand, his fingers extending beneath the main body of the retainer to elevate it until it engages the lower surface of the flat and a stack of cards or sheets held in the user's to lower the side at which the stops 8 are located and a stack of cards or sheets held in the user's other hand is dropped into place. As the stack slides over the flat top of the base between the guiding end pieces 5 and comes to rest against the stops 8, it arranges itself into a neat pile. When the user deposits the tray upon his desk the paper retainer is released and gravity pulls its lips 7 lightly down upon the edges of the cards or sheets of note paper. The sheet of metal forming the main body portion of the paper retainer has sufficient weight to releasably hold the stack of memo sheets in place.

When a user desires to make notes on the uppermost sheet of the memo paper, the weight of the base and of the paper retainer is sufficient to keep the device stationary while he is writing. Thus it is unnecessary for a person to use his other hand to hold the note sheet in place, that hand being available for holding a telephone, or reference material such as a book or paper from which notes are being taken.

After the uppermost sheet of paper has served its purpose it can easily be removed from the paper holder by slipping it sidewise or by pinching a finger and thumb together while in contact with the sheet, the friction between the fingers and the uppermost sheet being sufficient to with-

draw the edges of the sheet from beneath the lips 7. As a sheet is withdrawn gravity pulls the paper retainer 2 downwardly into engagement with what was the second sheet but then becomes the uppermost sheet, and the memo pad is again ready for further use.

In the size of the device as illustrated there is provided room for retaining a stack of memo sheets approximately one-quarter to three-eighths inch in thickness without having the uppermost sheet be too high above a writing surface for comfort and ease in writing thereon. Dimensions of the device, of course, may be changed in order to provide for the retention of different sized sheets of paper and of different quantities of paper. Such adaptations call only for different dimensions of the two units, which, though each is simple in structure, cooperate in so many ways to accomplish the objects of the invention and enhance the utility of the device.

The embodiment of the invention may be modified within the spirit and scope of the subjoined claims to meet various requirements.

Having described the invention, I claim:

25 1. A note paper holder comprising, in combination, a base having a substantially planar upper surface, and a paper retainer, said paper retainer having horizontally extending lips adapted to overlie and rest upon edges of the uppermost one 30 of a stack of loose note papers lying on the upper surface of said base and a body portion connecting said lips and located beneath said base, said lips of said paper retainer extending upwardly from said body portion, said paper retainer being 35 liftable to insert a stack of note papers beneath said lips and urged downwardly by force of gravity to retain the note papers on said base.

2. A note paper holder comprising, in combination, a base having a substantially planar upper surface, and a paper retainer, said paper retainer having at least one lip portion and a body portion extending substantially parallel to said lip, said lips being adapted to overlie and rest upon at least one edge of the uppermost one of a plurality of loose note papers lying on the upper surface of said base, and vertically extending paper stops adapted to position loose note papers in an orderly stack, said lips and stops projecting upwardly through said base and being freely movable vertically, said paper retainer being liftable to insert a stack of note papers beneath said lips and urged downwardly by force of gravity to retain the note papers on said base.

3. A note paper holder comprising, in combination, a base having a substantially planar upper surface and a hollow interior, slots in said upper surface leading to the interior of said base, and a paper retainer having a connecting portion located within said base, vertical end wall members extending upwardly through said slots, and retaining lips formed on the upper ends of said end wall members, said retaining lips being adapted to overlie and rest upon the edges of the uppermost one of a stack of note papers lying on the upper surface of said base, said paper retainer being freely movable vertically as a unit to insert a stack of note papers beneath said lips and being downwardly urged by force of gravity to press said lips on the stack of papers and to retain the papers on said base.

4. A note paper holder comprising, in combination, a base having a substantially planar approximately horizontally extending upper surface and a hollow interior, slots in said upper surface leading to the interior of said base, and a paper re-

tainer having a horizontal portion located within said base, vertical end members extending upwardly through said slots, vertically extending paper stops located at one side only of said retainer and extending upwardly through said slots, and horizontally extending retaining lips at the upper ends of said end members, said retaining lips being adapted to overlie and rest upon the edges of the uppermost one of a stack of note papers lying on the upper surface of said base, 10 said paper retainer being freely movable vertically as a unit to insert a stack of note papers beneath said lips and being downwardly urged

by force of gravity to press said lips on the stack of papers and to retain the papers on said base.
